(57) CLAIM

The ornamental design for a handbag, as shown and described.

DESCRIPTION

FIG. 1 is a front perspective view of a handbag, showing my new design;

FIG. 2 is a top perspective view thereof;

FIG. 3 is a front view thereof, the rear view being a mirror image of the front view;

FIG. 4 is a bottom view thereof;

FIG. 5 is right side view thereof, the left side view being a mirror image of the right side view;

FIG. 6 is a top view thereof;

FIG. 8 is a right side view thereof, the left side view being a mirror image of the right side view, shown with unclaimed portions of the handbag; and,

FIG. 9 is a front perspective view thereof, shown with unclaimed portions of the handbag.

The broken lines shown are included for the purpose of illustrating the unclaimed portions of the handbag and form no part of the claimed design.

1 Claim, 9 Drawing Sheets
